UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

THREAD-PARTING MECHANISM FOR LOOMS.

1,009,178.

Specification of Letters Patent. Patented Nov. 21, 1911.

Application filed March 15, 1911. Serial No. 614,517.

To all whom it may concern:

Be it known that I, ALONZO E. RHOADES, a citizen of the United States, and resident of Hopedale, county of Worcester, State of Massachusetts, have invented an Improvement in Thread-Parting Mechanism for Looms, of which the following description, in connection with the accompanying drawing, is a specification, like characters on the 10 drawing representing like parts.

This invention relates to mechanism employed in automatic filling-replenishing looms for parting near the shuttle the old filling-end which extends from the cloth to 15 the shuttle containing the filling-supply or bobbin about to be abandoned. In such mechanism provision is made for moving the thread-parting and clamping instrumentality in such manner as to bring the filling-end into the field of action of a temple 20 thread-cutter, to be severed thereby close to the cloth. Such a mechanism forms the subject-matter of United States Patent No. 922,511 granted to me May 25, 1909.

25 My present invention is an improvement thereon in certain particulars to be pointed out hereinafter, whereby I prevent the filling-end, whether or not severed by the temple thread-cutter, from being carried back 30 far enough to be whipped into the cloth. In the patented structure above referred to this fault sometimes occurs when the thread-parting mechanism is moved into operative 35 position in response to a call for filling replenishment.

The novel features of my present invention will be fully described in the subjoined specification and particularly pointed out in the following claims.

40 Figure 1 is a transverse section on the line 1—1, Fig. 2, of a portion of a loom and the thread-parting mechanism, with my present invention embodied therein, the parts being shown in normal position; Fig. 45 2 is a top plan view of the greater portion of the mechanism illustrated in Fig. 1 with the parts in the same position; Fig. 3 is a detail in plan showing the thread clamping and parting instrumentality in position to 50 clamp and part the old filling-end with the relative position, at such time, of the guard or catcher which co-operates with such filling-end to prevent the latter from being carried into the cloth.

55 The lay A³, transerrer f' to remove the

filling-carriers or bobbins b^x from the filling-feeder or hopper F to the shuttle S when in the box B at the replenishing side of the loom; the controlling rock-shaft d' and its adjuncts; the horizontal stud 2 on which 60 rocks the yoke-arm 4, 5, the pin 3^x thereon operatively connected with rock-shaft d' by the arm d¹² and jaw d¹⁴ governed by the spring S^x; the shuttle-feeler 9 having its shank 10 mounted to swing laterally in the 65 carrier 4, 5 and also with the latter in a fore and aft direction, said shank having the follower arm 15 co-operating with the slotted cam-ear 17 to control the lateral swing of the shuttle-feeler; the fixed and movable 70 blades 16', 17' carried by the feeler and the plate 19 constituting the fixed member of the thread-clamp, and the heel 20 which operates the movable member 17' of the clamp and thread-parter, are and may be all as in 75 my patent above referred to, and operate as therein set forth. The temple T, Fig. 2, and the thread-cutter t^x thereon are also usual and well known in the art. Herein, as in my patent, the setting or opening device for the clamping and parting instrumentality is mounted upon the upturned arm 21 fulcrumed at 22 and provided with the spring-controlled cam-rib 25 on the rearwardly extended end 27 of the arm 21. 80

It will be understood that when filling-replenishment is called for the turning of the rock-shaft d' causes the shuttle-feeler to be swung rearward and laterally into the position shown in Fig. 3, supposing the shuttle to be properly boxed for replenishment, and the advancing lay strikes the heel 20 to cause the appropriate devices to first clamp and then to part the filling-end, indicated at t, Fig. 2, the parting of the filling-end being 95 at the side nearest the shuttle.

It will be remembered that the clamp and parter have been opened by the action of the cam-rib 25 on the pin 28 as the shuttle-feeler is moved to operative position.

100 Referring to Fig. 2 let it be supposed that the old filling-end which is clamped by the members 17' and 19 has not yet been parted by the temple thread-cutter t^x when the shuttle-feeler returns to its normal position, or if 105 parted thereby lies in about the position indicated at t¹⁰, Fig. 2. If now replenishment is again called for the rearward movement of the shuttle-feeler to operative position will carry the end t¹⁰ back, should it stick 110

in the opened clamp, into such a position that it might be easily whipped back into the cloth.

Sometimes the severed piece of filling does 5 stick in the clamp after the latter is opened, and so, too, replenishment is sometimes called for before the temple thread-cutter has severed the filling-end and in either case 10 there is the danger that the filling-end t^{10} will be carried back into the cloth and make a bad place therein.

I will now describe the simple and effective means which I have herein provided for so guarding or catching the filling-end that 15 under no circumstances can it be carried back into the cloth.

The rear end of the extension 27 of the arm 21 is, in accordance with my present invention, turned laterally and horizontally 20 at 50, toward the shuttle-feeler 9, and its extremity is provided with a guard 51 having a notch 52 therein open toward the front of the loom, and as shown in Fig. 2, this guard is located back of the tip of the shuttle-feeler when the latter is in its normal 25 position and between the path of movement thereof and the temple T.

The old filling-end t^{10} may rest upon the extension 27, as contemplated in my patent 30 before referred to, or it may rest upon the lateral prolongation 50 of such extension, as I have shown it in Fig. 2.

When filling-replenishment is called for 35 the shuttle-feeler 9 is moved rearward and to the right, Fig. 2, into its operative position shown in Fig. 3, and such movement carries the filling-end into the notched guard 51, see Fig. 3, so that if the thread is not released completely when the members of the 40 clamp are opened the guard will act upon the thread or filling-end t^{10} and pull its end free from the clamp. The guard thus 45 catches the old filling-end and holds it from being carried back as the shuttle-feeler moves to operative position, and thereby prevents the old filling-end from being carried 50 near enough to the lay to be whipped or carried into the cloth. Even should such piece of thread t^{10} be still unsevered by the temple 55 thread-cutter the guard 51 will still operate to hold it away from the danger point, for unless the loose end is near the shuttle path it can not be carried back into the cloth.

The coöperation of the guard 51 with the 60 old filling-end is effected just about the instant when the thread clamping and parting device on the shuttle-feeler is opened or set for operation, and by mounting the guard on the lateral prolongation 50 of the extension 27 the guard is brought as close as possible to the thread clamping and parting device, and the proper action of the guard is insured.

When the filling-end is clamped and part- 65 ed the slight rise of the tip of the shuttle-

feeler as it swings forward and to the left back to normal position serves to carry the clamped filling-end up and over the guard, the rear face thereof being rounded or convexed, as at 53, to facilitate the passage of 70 the thread thereover.

Having fully described my invention, what I claim as new and desire to secure by Letters Patent is:

1. In an automatic filling-replenishing 75 loom, a shuttle-feeler adapted to be swung rearwardly and laterally into operative position when replenishment is called for, a thread clamping and parting instrumentality mounted on the feeler, to clamp and part 80 the old filling-end near the shuttle, an arm having means to set such instrumentality when the shuttle-feeler moves to operative position, and a device carried by said arm to engage and hold, at a point between the 85 selvage and the thread clamping and parting instrumentality, the old filling-end previously clamped and parted and to prevent rearward movement of such filling-end when the shuttle-feeler is moved to operative 90 position, whereby the filling-end can not be carried back into proximity to the path of the shuttle.

2. In an automatic filling-replenishing 95 loom, a shuttle-feeler adapted to be swung rearwardly and laterally into operative position when replenishment is called for, a thread clamping and parting instrumentality mounted on the feeler, to clamp and part 100 the old filling-end near the inner end of the shuttle, an arm having means to set such instrumentality when the shuttle-feeler moves to operative position, a lateral prolongation on said arm turned toward the shuttle-feeler, and a guard on said prolongation 105 having a frontwardly open notch to catch and hold, at a point between the selvage and said clamping and parting instrumentality, the old filling-end previously clamped and parted and insure the disengagement 110 thereof from the clamping and parting instrumentality when the latter is set for operation upon movement of the shuttle-feeler to operative position.

3. In an automatic filling-replenishing 115 loom, a temple-thread-cutter to part the old filling-end adjacent the cloth, a shuttle-feeler movable into position to coöperate with such filling-end when replenishment is called for, a thread clamping and parting 120 instrumentality mounted on said feeler, to clamp and part the old filling-end near the shuttle, means to set for operation such instrumentality upon movement of the shuttle-feeler to operative position, and an upwardly and frontwardly notched guard interposed between the temple thread-cutter and the shuttle-feeler and adjacent the path of movement of the latter, to engage and hold a 125 previously clamped and parted filling-end 130

and prevent rearward movement thereof when the shuttle-feeler is again moved to operative position, the coöperation of the guard with the old filling-end at such time insuring its disengagement from the clamping and parting instrumentality.

4. In an automatic filling-replenishing loom, a temple-thread-cutter to part the old filling-end adjacent the cloth, a shuttle-feeler movable into position to coöperate with such filling-end when replenishment is called for, a thread clamping and parting instrumentality mounted on said feeler, to clamp and part the old filling-end near the shuttle, means to set for operation such instrumentality upon movement of the shuttle-feeler to operative position, an upright arm on which said means is mounted, a lateral prolongation on the arm, and a guard on the upper side of said prolongation adjacent the path of movement of the shuttle-feeler, to engage and hold from rearward move-

ment a previously clamped and parted filling-end when the shuttle-feeler is again moved to operative position, such action of 25 the guard also serving to effectually disengage the old filling-end from the clamping and parting instrumentality when the same is set for operation.

5. In a loom, in combination, a feeler 30 thread-cutter, and means coöperating with the old filling-end between the selvage and the feeler thread-cutter to prevent the said thread-cutter from carrying rearwardly the old filling-end due to a previous operation 35 of the thread-cutter.

In testimony whereof, I have signed my name to this specification, in the presence of two subscribing witnesses.
